UNITED STATES PATENT OFFICE.

WILLIAM F. MALLOY, OF ALLEGHENY, ASSIGNOR TO THE PITTSBURGH BRASS COMPANY, OF PITTSBURG, PENNSYLVANIA.

DESIGN FOR A LAVATORY-TABLE FRAME.

SPECIFICATION forming part of Design No. 22,466, dated May 23, 1893.

Application filed January 24, 1893. Serial No. 459,629. Term of patent 7 years.

To all whom it may concern:

Be it known that I, WILLIAM F. MALLOY, a resident of Allegheny, in the county of Allegheny and State of Pennsylvania, have invented a new and original Design for Lavatory-Table Frames; and I do hereby declare the following to be a full, clear, and exact description thereof.

My design relates to lavatory table frames, and it consists in a table frame composed of a lavatory support formed of receding corrugated moldings and corner angles and wall brackets correspondingly receding and corrugated and projecting beyond the moldings, and legs connected to the corner angles and having backwardly curved upper portions and vertical body portions.

It also consists in the above described support composed of receding corrugated moldings and corner angles and wall brackets correspondingly receding and corrugated and projecting beyond the moldings.

In the accompanying drawing the lavatory table frame embodying the design is illustrated by a perspective view, the lavatory resting thereon being shown in dotted lines.

The lavatory table frame is composed of the lavatory support and the legs therefor, which are of the following design. The lavatory support is composed of the receding corrugated moldings *a b* which fit into and are connected to corner angles *c*, these corner an-

gles being receding and correspondingly corrugated to the moldings *a b*, and the corner angles projecting out beyond the moldings. 35 At the ends of the side moldings *b* are the wall brackets *d* which are also formed receding and correspondingly corrugated to the moldings *b*, and which also project beyond the moldings as shown. The lavatory support 40 above described forms a segregable part of the device. The legs connected to the lavatory support, and forming in connection therewith the table frame, are secured to the corner angles *c*, and each leg has the backwardly 45 curved upper portion *e* and the vertical body portion *f*. The lavatory table frame thus gives the effect of an ornamental receding support for the body of the lavatory and the legs in conjunction with that support, a further effect of the ornamental receding support and receding legs.

What I claim is—

1. The design for a lavatory table frame herein shown and described. 55
2. The design for a lavatory support herein shown and described.

In testimony whereof I, the said WILLIAM F. MALLOY, have hereunto set my hand.

WILLIAM F. MALLOY.
